R. F. HALL.
SPARKING PLUG.
FILED MAY 24, 1920.

Inventor:

Robert Frederick Hall
By his Attorneys
Badrin Wright

UNITED STATES PATENT OFFICE.

ROBERT FREDERICK HALL, OF MOSELEY, NEAR BIRMINGHAM, ENGLAND.

SPARKING PLUG.

Application filed May 24, 1920. Serial No. 383,830.

To all whom it may concern:

Be it known that I, ROBERT FREDERICK HALL, a subject of the King of Great Britain and Ireland, residing at Moseley, near Birmingham, in the county of Warwick, England, have invented certain new and useful Improvements in Sparking Plugs; and I do hereby declare the following to be a full, clear, and exact description of the invention, such as will enable others skilled in the art to which it appertains to make and use the same.

This invention relates to sparking plugs for internal combustion engines and is designed to provide devices of the class in question which are more efficient in use, more economical and possess other advantages as compared with sparking plugs as at present in use.

One of the principal objects of the invention is to provide a plug in which both the electrodes or sparking points are furnished in a body adapted to be placed in a casing permanently attachable to the engine, so that the said body can be easily removed for the purposes of cleaning the sparking points, or for replacing it by or interchanging it for a different body to suit requirements.

Another object of the invention is to provide improved means for cooling or ventilating the plug.

A further object of the invention is to provide an efficient gas tight joint to the plug, in spite of the carrying temperatures to which it is exposed, and irrespective of the fact that the insulator body carrying both the electrodes can be easily removed.

A further object is to provide means for adjusting with great accuracy the dimensions of the spark gap to suit requirements.

Other objects of the invention will be hereinafter mentioned with reference to the particular constructional embodiments of the said inventions shown on the accompanying drawing.

In order that the said invention may be clearly understood, I will proceed to describe the same with reference to the accompanying drawing, in which:—

Fig. 1 is a vertical axial section of a sparking plug constructed according to the primary method of carrying out my invention.

Fig. 2 is an elevation of the same plug. 55
Fig. 3 is an elevation of the outer casing detached.

Fig. 4 is a plan of the same. 55
Fig. 5 is an elevation of the tube enclosing the insulated electrode. 60

Fig. 6 is a plan of same. 60
Fig. 7 and Fig. 8 are elevation and plan respectively of a castellated ring serving to retain the insulated electrode in its adjusted position. 65

Fig. 9 is a view of the ferrule carrying the earthed electrode.

Fig. 10 is a view of the sparking point detached from the ferrule.

Fig. 11 and Fig. 12 are vertical section 70 and plan respectively of the cap for retaining the insulated electrode and other parts in position in the outer body.

Fig. 13 is a separate view of the insulated electrode. 75

Fig. 14 is a sectional view of a modified form of plug.

Fig. 15 shows the carrier for the insulated and earthed electrode of Fig. 14 removed from the outer body. 80

Fig. 16 is a horizontal section of the central sparking point, and

Fig. 17 is a view similar to Fig. 15 of a further modification.

Figs. 18 and 19 are views of modified 85 forms of block to which the end of the high tension cable is attached.

The same numerals of reference are employed to denote the same parts in all the views. 90

Referring to the construction shown in Figs. 1 to 13, the main or outer body 1 of the sparking plug is formed from hexagon section drawn steel, provided with fins 2 for facilitating the radiation and cooling, and 95 with holes 3, drilled through the flats.

The end 4 of the body 1 is machined down to form a thread so that it is adapted to screw into the cylinder wall. The main plug body may remain permanently in position as 100 no sparking point or electrode is rigidly connected thereto.

The main body 1 is tubular and is provided at 5 with an annular valve like seating machined internally near the screw 105 threaded end 4. 6 is a screw thread, at the upper end of the body 1 to receive the retaining cap hereinafter mentioned.

The detachable insulator body, which is adapted to fit into the main body 1, just described is constructed as follows:—

7 is a piece of round steel having drilled 5 holes at each end. One of these holes 8 is adapted to receive a nickel sparking point 8^a (Fig. 13) constituting the central or insulated electrode. This sparking point is preferably made from nickel rod or wire, 10 one end of which forms a tight fit in the hole 8 whilst towards its opposite end it is cranked at 8^b for a purpose hereinafter described.

The other hole 9 at the opposite end of the member 7 is adapted to receive the terminal 15 plug of the high tension electrode.

Round the central steel body 7 is coiled or folded a thin strip of mica 10, until an insulating covering of the required thickness and diameter is formed, or some other 20 insulating material may take the place of the mica if desired.

11 is a steel tube shown separately in Figs. 5 and 6 over the mica or other insulation 10 and to form a firmly attached outer covering 25 or retainer when pressed, shrunk or otherwise fixed in position.

The outer surface of the tubular body 11 is provided with a longitudinal groove or channel 12 extending from its upper end to 30 within a short distance of its lower end 13, the latter being turned with a valve like seating corresponding substantially to the before mentioned seating 5, on the main body 1. The upper end of the tube 11 is 35 provided with a flat facing at 14 upon which the retaining cap is adapted to press.

15 is an open ended ferrule shown separately in Fig. 9. This ferrule which is adapted to fit over the outside of the lower 40 end of the tube 11 and is preferably made of steel conforms substantially to the lower end of said tube and is provided with a stepped portion at 16 corresponding to and adapted to be gripped between the valve like seating 45 5 and 13 on the casing 1 and the tube 11 respectively. Its lower end is cut off at a sharp angle at 15^a and at or near its lower end is drilled to receive a nickel sparking point 17 (Fig. 10) which fits into said hole 50 and riveted or otherwise secured in position as shown in Fig. 1, so as to project inwardly towards the central insulated electrode 8^a.

18 is a projecting point or tooth in the upper edge of the ferrule 15 for a purpose herein- 55 after explained. 19 (Figs. 7 and 8) is a ring or bush adapted to fit over the outer surface of the tube 11, the lower end of which is formed with a series of castellations 20, the grooves of which are of sufficient width to 60 engage the tooth or point 18 on the upper edge of the ferrule. One of the teeth of the castellations is bent inwardly as shown at 20^a to engage the longitudinal groove 12, on the outer surface of the tube 11, so that the

tube 11, the ferrule 15 and the ring 19 are 65 locked together relatively to one another. By this means the length of the spark gap between the sparking point 17 on the ferrule 18 and the end of the central sparking point 8^a may be adjusted by first lifting the castellated ring 19 upwardly until the tooth or point 18 on the ferrule is free of the castellations and on rotating the ring 19, the tubular member 11 carrying the insulated central electrode will also be rotated, and as the end 70 of the sparking point 8^a is located eccentrically of the axis of rotation, the length of the spark gap will be increased or decreased 75 according to the degree of rotation. When the points have been adjusted the ring 19 is 80 again moved to engage the tooth 18 of the ferrule and the latter is locked in its adjusted position so that when the retaining cap 21 is screwed down into the body 1 no movement of the central electrode and the 85 earthed electrode relatively to one another is possible. 21 (see Figs. 11 and 12) is the retaining cap which is of stepped tubular form externally screw-threaded at 22 to engage the screwed portion 6 of the body 1 and 90 internally screwed at 23 to receive a screwed cap or adaptor 24. The retaining cap 21 is provided with an internal flange or shoulder 21^a adapted to engage the upper flat surface 14 of the tube 11 and with a central perforation 21^b through which the mica or other insulation 10 projects.

The upper outer surface of the screwed cap or adaptor 24 is milled or knurled at 24^a to facilitate its attachment. Within the cap 100 24 is placed a block of insulating material 25 say for instance vulcanized fibre, which is provided with a central recess, the lower end of which is stepped at 26 whilst the upper portion of said recess may be tapered at 27 105 to receive the end of the long extension cable 28 from the magneto or coil. The latter is secured in the following manner. The ends of the upper strands and the cable are cut off flush at 29 and then a small wire plug 110 terminal 30 is screwed up into the cable among the copper strands thereby swelling out the end of the cable as seen clearly in Fig. 1 and making it of larger diameter than the remaining portion so that it will not pull 115 through the hole in the block 25 and so that any pull only tends to cause the end of the cable to be gripped more tightly.

The hole 9 is preferably drilled deeper than the length of the projecting terminal to 120 allow for any variation in length in the manufacture of the different parts.

It will be seen that with the foregoing construction, access may be readily obtained to the body carrying both electrodes for the purpose of cleaning adjusting inspecting or replacing the same, as when the retaining cap 21 is unscrewed the tube 11 with the

central insulated electrode and the ferrule 15 carrying the earthed electrode may each be removed without removing the main or other body 1 from the engine cylinder and 5 without detaching the high tension cable from the adaptor 24 and block 25.

Referring now to the construction shown in Figs. 14, 15 and 16, it will be seen that the tube 11 and the ferrule 15 have been combined to form one member carrying the earthed electrode. In this construction the ferrule like member 31 is bifurcated at its lower end at 32. At or near the lower end of each arm is provided a spherical or other appropriately shaped sparking point 33 riveted or otherwise secured in position as shown in Fig. 15. The central member 7 forming the central insulated electrode is in this construction formed with a central rod 24 the lower end of which is screw-threaded to receive a nickel sparking point 35 consisting of a plug or the like, the outer surface of which is stepped or formed with two cam like surfaces 35^a, 35^b arranged in such a manner as to enable the length of the spark gap to be adjusted by rotation of the plug 35, by increasing or decreasing the distance between the sparking point 33 of the earthed electrodes and the points of nearest approach on the cam like surfaces 35^a.

The high tension cable 28 in this construction is attached to a fibre block 36 in the manner already described, but in order to enable the retaining cap 21 to be screwed down or the screwed cap or adaptor 37 carrying the high tension cable to be rotated without twisting the cable or otherwise loosening by the connection between it and the wire terminal 30, the outer surface of the fibre block 36 is encased in a ferrule 38 of thin sheet metal. By this means when the retaining cap 21 or the screwed adaptor 37 is rotated the ferrule 38 which forms a sliding fit against the inner surface of the adaptor will remain stationary and still securely hold the end of the high tension cable 28 in position. This method of attachment has the further advantage that once the end of the cable with the terminal 30 has been secured in position in the block 36 it will not need to be detached and the retaining cap 21 may be easily removed from the body 1 and remain attached to the adaptor 37 and the cable 28 when the electrodes are to be removed thus saving considerable time and preventing the loss or damage to the parts, which often happens with plugs as at present constructed.

The construction shown in Fig. 17 is similar to that shown in Fig. 15 except that the screwed cam like central sparking point is replaced by a spherical member 40 provided with a central perforation to receive the reduced end of the central electrode 34, the

end of the latter being riveted over so as to 65 retain the sparking point in position. In this form the adjustment of the spark gap is effected by springing or bending the bifurcated ends or arms 32 towards or away from the central insulated electrode. 70

Figs. 18 and 19 show two modified forms of blocks of insulating material to which the end of the high tension cable 28 is attached. In the form shown in Fig. 18 the block 25^a is formed with an enlarged recess 26^a extending upwardly from the bottom surface whilst the central hole is tapered at 27 as in the construction shown in Fig. 1. The end of the high tension cable 28 is secured in the plug 25^a in a similar manner to that described in connection with Fig. 1 whilst the lower outer surface of the recess 26^a forms a skirt when the plug is assembled which surrounds and protects the upper edge of the insulating covering 10 of the central electrode. The form shown in Fig. 19 represents an alternative plug of fibre, porcelain or other insulating material which may be used when it is desired to connect the high tension cable in the usual manner by an eyepiece engaging the screwed rod 42. In this construction the block 25^b is provided with a central recess, as in the previous construction whilst the central electrode terminal 30 is extended upwardly through the 95 top of the plug and is formed with a square or other suitably shaped shoulder 43, fitting into a similarly shaped hole in the block 25^b the rod being secured therein by a nut 44 by means of which the eye piece attached to the 100 end of the cable is connected thereto, whilst the block is formed with a separately extending neck projecting through the hole in the top of the screwed adaptor 24 (Fig. 1).

What I claim as my invention and desire to secure by Letters Patent of the United States of America is:—

1. In a sparking plug, the combination of a body portion provided internally with a valve like seating, a central electrode carried by a covering of insulating material, a tubular member in which said insulating covering is secured, a ferrule carrying said tubular member and having a valve like portion adapted to engage the seating in the 110 body portion, a sparking point on said ferrule and means for securing said tubular member and ferrule against independent rotation after the length of the spark gap or gaps has been adjusted. 120

2. In a sparking plug, the combination of a body portion provided internally with a valve like seating, a central electrode carried by a covering of insulating material, a tubular member in which said insulating covering is secured, a ferrule carrying said tubular member and having a valve like portion adapted to engage the seating in the 125

body portion, a sparking point on said ferrule, a sparking point on said central electrode, a projection on said ferrule, a locking ring surrounding said tubular member, a

operating with the projection on the ferrule to prevent independent rotation of the ferrule and tubular member for the purposes 10 set forth.

5 projection on said locking ring engaging a longitudinal groove in said tubular member and spaced recesses on said locking ring, co-

In witness whereof I affix my signature.

ROBERT FREDERICK HALL.
